UNITED STATES PATENT OFFICE.

EMIL G. SAUER, OF BROOKLYN, NEW YORK, ASSIGNOR TO THE LOWELL MANUFACTURING COMPANY, OF LOWELL, MASSACHUSETTS.

DESIGN FOR A CARPET.

SPECIFICATION forming part of Design No. 20,805, dated June 2, 1891.

Application filed January 23, 1891. Serial No. 378,845. Term of patent 3½ years.

To all whom it may concern:

Be it known that I, EMIL G. SAUER, of the city of Brooklyn, county of Kings, and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet, showing my new design.

My design consists of the body part A, of "rosettes" placed regularly and connected by a straight "lattice-work" and a serpentine lattice-work running underneath the straight lattice-work and connecting at points between 20 the rosettes.

What I claim as new, and desire to secure by Letters Patent, is--

The design for carpets, consisting of the body part A, substantially as shown.

EMIL G. SAUER.
